UNITED STATES PATENT OFFICE.

NAPOLEON J. PERRY, OF NASHVILLE, TENNESSEE, ASSIGNOR TO MAY HOSIERY MILLS, OF NASHVILLE, TENNESSEE, A CORPORATION OF TENNESSEE.

KNITTING MACHINE.

Application filed December 22, 1919, Serial No. 346,681. Renewed July 22, 1927.

My said invention relates to a pattern mechanism for knitting machines and consists in the combinations and arrangements of elements hereinafter described and particularly set forth in the accompanying claims.

The invention has for its purpose to provide a knitting machine convertible to knit plain, ribbed 1, or plain and ribbed, to the 10 end that articles of apparel (particularly hosiery) may be completely knitted from the toe to the top of the leg without requiring the transfer of the article from one machine to another, as is now the practice.

15 The invention has for its further purpose to provide an attachment for plain knitting machines adapted to be brought into operation as required to supplement plain knitting with rib knitting, or to be used independently for rib knitting alone; and 20 wherein the attachment is operable through the mechanism which actuates the plain knitting.

Another purpose of the invention is to 25 equip a plain knitting machine with apparatus for rib knitting wherein said ribbing apparatus is automatically set to be worked through that means which automatically operates the plain knitting machine to change 30 from circular to reciprocable knitting, or vice versa.

The invention further contemplates the provision of a pattern form that is actuated through the aforesaid control of the plain 35 knitting machine, that will bring the rib knitting mechanism into operation to knit ribbing at the proper periods in the manufacture of the article, and which is adapted to be altered or changed at will.

40 The invention further proposes to provide the machine with devices which will automatically operate to disconnect the means operating the knitting head from the drive in the event of breakage of one or more of 45 the needles, or by the accumulation of yarn in the knitting head from whatever cause.

The invention, as disclosed herein, is adapted for attachment to any standard type of circular knitting machine, and the 50 range of adjustment, timing, and combinations of the several elements, is such that the equipped machine is capable of manufacturing a wide variety of stockings by plain ribbed circular or reciprocable knitting, or 55 any combination of these.

The machine embodies the construction disclosed in my co-pending application for U. S. Patent Serial No. 146,917, dated Feb. 6, 1917, of which this application is a continuation as to a portion of all common subject matter and proposes further improvements on the construction shown therein. 60

The invention is disclosed by way of illustration in the accompanying drawings, 65 wherein

Figure 1 is a front elevational view of the machine complete.

Figure 2, a top plan view of the same,

Figure 3, a plan view of the rotating head taken on line 3—3 of Figure 1, 70

Figure 4, a transverse sectional view taken on the line 4—4 of Figure 1,

Figure 5, a sectional view on the line 5—5 of Figure 1,

Figure 6, a horizontal sectional view taken 75 on the line 6—6 of Figures 1 and 4, and with certain parts omitted,

Figure 7, a fragmentary plan view of the head showing the automatic stop device,

Figure 8, a cross section through a portion 80 of the head showing the automatic stop device and a part of the fabric take-up device,

Figure 9, a side elevation of the operating mechanism of the fabric take-up,

Figure 10, the operating pawl for the pattern wheel, 85

Figure 11, a central sectional view of the dial and dial cap taken on the line 11—11 of Figure 13,

Figure 12, a similar view taken on the line 90 12—12 of Figure 13.

Figure 13, an inverted plan view of the dial cap,

Figure 14, a diagrammatic view, partly broken away, of the dial and showing the 95 needles in different positions of operation,

Figure 15, a detail view of a cam element of the dial cap,

Figure 16, a detail sectional view showing the tensioning device for the movable guide 100 cams,

Figure 17, an enlarged view of one of the dial cap cam actuating devices,

Figure 18, a similar view of the other dial 105 cap cam actuating device,

Figure 19, a top plan view of the device shown in Figure 18.

Figure 20, a detail perspective view of the controlling portion of the automatic stop device of the machine, and 110

Figure 21, a detail view of the operative portion of said stop device.

Referring to the construction in further detail, and wherein like reference characters indicate corresponding parts in the several figures, 25 designates the frame of a standard plain knitting machine of the type illustrated in the patent to Mayo No. 726-178, granted April 21, 1903, having a driving shaft 26 journaled therein and adapted to be driven from a suitable source of power by a pulley arrangement 27. Said driving shaft is fitted with clutch elements 28 and 29, for rotating the knitting head 30, for circular knitting through the bevel gears 31 (only one being shown); or said knitting head may be oscillated for reciprocable knitting, through the clutch elements 29 and 33.

The transmission for operating the knitting head, to knit by reciprocable knitting, comprises a pinion 34 coupled to rotate with the shaft 26 through the clutches (29 and 33) and meshes with a larger pinion 35 journaled on the shaft 36. Said pinion 35 carries a wrist-pin 37 connected with the connecting-rod 38 to operate the gear-segment 39; and said segment meshes with the gear wheel 40 to impart oscillation thereto and this being connected with imparts like motion to the bevel gear 31 and operates the knitting head for reciprocable knitting. The clutch element 29 is actuated to connect with either of the clutch elements 28 or 33, both normally free to rotate on the shaft 26, for imparting rotation or oscillation to the knitting head for circular or reciprocable knitting, through the clutch arm 41 fulcrumed on the frame at 42 and operated through engagement with the cam wheel 43 which is fixed to a cam shaft 44 mounted on the frame 25.

The cam wheel 43 is adapted to be operated with a step-by-step movement from the driving shaft, through the following mechanism; a hub 46 on the cam shaft 44 has a ratchet wheel 45 loosely mounted thereon and a sprocket wheel 47 is fixed to the ratchet, as in the Mayo patent. A chain 48 travels on this sprocket and said chain constitutes the timing element of the machine. The ratchet wheel 45 is intermittently turned by the pawl 49, actuated by the crank arms 50, forming a part of the hub 53 of the segment 39, the pawl being mounted between them on a pivot 252. The mechanism thus far described operates only the ratchet wheel 45 and the sprocket wheel 47, carrying the chain 48, while the shaft 44 and the cam wheel 43 remain stationary.

The pattern wheel or form 133 is loosely mounted on hub 46. This wheel is intermittently rotated by the pawl 249 mounted on the pinion 250 by means of a wrist pin, and said pinion gears with the relatively larger pinion 35 and thus said pattern wheel 65 is moved at an accelerated speed with re-

spect to the ratchet wheel 45 (see Figures 4, 9 and 10). A modified form of drive in which a single pawl actuates both the hub and the pattern wheel is illustrated in my application No. 146,917 above referred to.

Pinion 250 is one-half the size of gear 35, and therefore rotates twice for each rotation of gear 35. Pawl 249 is therefore moved twice for each movement of pawl 49, the latter being attached to segment 39 which is oscillated at each rotation of gear 35. The shaft 44 has a notched disc 55 fixed thereon which is engaged by a pawl 56 pivoted to the lever 57, fulcrumed to the frame at 58, deriving movement from the hub 53 of the segment gear 39, through the cam 52, for moving the arm in one direction, and the retraction spring 60 operating to return said arm. The pawl 56 is normally held inoperative by the dog 61 pivoted on the frame 25 (see Figure 6) and said dog is tensioned, by the spring 59, to engage with one edge of the chain and is formed with a tail-piece 62 (see Figure 4) normally coacting with the pin or stud 63 of the pawl 56, to hold the latter out of engagement with said notched disk 55. Several of the shiftable units of the chain 48 are provided with lugs 64, whose function is to engage with dog 61 and lift the latter to release the pawl 56, when said pawl may engage with a notch on the disk 55 and impart movement thereto. Said disk 55 is fixed to the cam wheel 43 and thereby imparts movement to said cam wheel to actuate the clutch-shifting arm 41 to engage with one or the other clutch elements 28 and 33, accordingly as the machine is to operate by circular knitting or reciprocable knitting, and this is predetermined by the number and location of lugs 64 on the chain 48 which may be arranged as required to effect the pattern to be knitted.

A second cam wheel 65 is fixed on the shaft 44 and has for its function to shift the cam plate of the knitting head and to manipulate the yarn carrier, as in the Mayo machine. A notched disk 66 is secured to said cam wheel 65 and is engaged and operated by a pawl 67 pivoted on the lever 68 which, in turn, is moved through engagement with the roller 268 journaled on the gear segment 39. A retraction spring 69, anchored to the frame returns said lever 68. The notches on the disk 66 are disposed to supplement the notches on the disk 55, to the end that the latter disk 55 will be moved during those periods when its own operating pawl is inactive, the two disks 55 and 66 having blank spaces separating individual notches or groups of notches and having their respective notches so located as to form virtually a single disk notched about its periphery. The disk 55 has in the exact structure shown in the drawings only four

notches and by this arrangement, the cam wheel 43 is moved that number of times to shift the clutch in accordance with the arrangement of lugs 64 on the chain 48; the disk 55 must be moved up notwithstanding its blank periphery, and this is done by the notches in the disk 66 which are located angularly with respect to the blank periphery of said disk 55 because of the different points of contact of their respective pawls; and where there are notches on the disk 55, there are none on the disk 66. In other words, the disk and pawl (66 and 67) provide an auxiliary device for insuring the running of the machine in proper timed relation. The foregoing structure is substantially that of the Mayo machine, and the present invention provides an attachment consisting of a knitting head having dial needles mounted on the cylinder cam-ring of the knitting head of the machine proper and various connecting and cooperating mechanisms. The support for the head consists of an arm 70 secured to the frame 25 of the machine in any suitable manner, having an annular portion 71 supporting a series of inwardly disposed and cam operated slidable bolts 72. Each of said slidable bolts at its inner end engages a notch in a ring 73 mounted on shaft 75 disposed concentric with the cylinder 76 of the cylinder needles (see Figures 1 and 2). The several bolts 72 engaging the shaft supporting disc are to prevent rotation of the disc and are displaced in succession by the respective cams at opposite sides of the yarn guide 74 according to the direction of movement (see Figure 2) and said yarn guide is in turn carried by the revolving head after the usual manner. A dial 77 constructed to receive a plurality of dial needles 78, is fitted on the shaft 75 and located within the cylinder 76, and remains stationary therein by reason of the arms 72 as hereinbefore described.

A dial cap 82 is secured to the shaft 75 and carries the elements for actuating the dial needles at the periods predetermined by the pattern forms heretofore referred to. Said elements consist of a pair of plates 83 and 84 mounted to slide radially in the ways 85 formed on the underside of said dial cap, and are adapted to be actuated by the links 86 and 87 engaging pins 88 secured to the plates 83 and 84 and working in slots 89 formed in the body of the dial cap 82.

The plates 83 and 84 are constructed with cams 90 and 90' which act to project the needles of the dial through the rotary motion of the dial cap. Other cam elements 91 and 91' formed on each of the slidable plates, operate to limit the movement of the projected needles, forming a cam way 92 to receive the butts 93 of the dial needles 78 (see Figures 11, 12 and 13) to move said needles inwardly and outwardly as required.

Two pairs of guide members or wing cams 95 pivotally mounted on studs or pins 96 (Figures 12, 13 and 14) are tensioned each against its adjacent projecting cam 90 by the pair of springs 97, to the end of forming 70 a continuous adjustable cam and cam-way 92 through which the butts 93 of the dial needles may freely move. Said pair of guide members 95 are made movable to the end that they will contact with the surfaces 75 of the cams 90, 90' in any position of said cams in their operation.

Retracting cams 197 (Figs. 11 and 13) are positioned to act on the needles shortly after they have been advanced by the projecting cams 90, 90'. A gate 99 (hereinafter described) and a guard cam 197' follow in succession after each retracting cam and serve with guard cams 91, 91' to complete the outer wall of the cam-path. The cams 85 197 and 197' are secured to the cap by screws 98.

It sometimes happens that the dial needles 78 become broken, and in order to facilitate their removal in such instances, with the least trouble, an access passage, closed by the piece 99, is provided and said piece is detachably secured to the underside of the dial cap 82 by a spring-pressed stud 100 that works within a chamber 101 formed in said dial cap 82. Said stud 100 has a swiveled head 94 for drawing and retaining the piece 99 within the recess 101 giving access to the needles.

The slide 83 is adapted to occupy various 100 positions according to whether the needles are to knit, tuck or remain inactive in the "welt" position. In the last position the needles are idle and substantially stationary, but may either be empty, or be 105 holding previously knit loops for making a welt.

The slide 84 also occupies different positions, depending on whether or not the needles are to be projected, as to clear the 110 latches for casting off the work, or to open the latches prior to commencement of knitting on the dial needles, or opened prior to knitting on the dial needles.

The movement of the needles for casting off and latch opening is accomplished by the cam 90' connected to the link 86, and said link is connected to the arm 102 on the post or shaft 103 pivotally mounted in the block 71. A pinion 104, secured to the shaft 103 115 meshes with a similar pinion 105 on the shaft 106, likewise journaled in said block 71, to the end that the movement of either shaft 103 or 106 will cause a like movement of the other in the opposite direction. An arm 107 is mounted on the shaft 106 and acts, when engaged by the obstruction or trip 108, to move cam 90' to its outermost position, when the brush 109 on the support 120 125 130 135 140 145 150 needles to open the same. In this position of the cam, the dial head makes a suitable number of revolutions to insure that the latches of all of the needles have been 5 opened. An arm 113, on the shaft 103, contacts with the obstruction or trip 114 to move the link 86 for carrying the cams half-way in; and immediately following this, the arm extension 115, being engaged by the trip 114, 10 moves the cams all the way in. The function of the arms 107, 113, and 115, is to contact with the trips 108 and 114 for the purpose of positioning the cam 90' to project the needles to have the latches 111 opened, 15 when knitting is to begin on the dial needles and to move said needles fully in with said latches opened, thus leaving the needle hooks 112 in condition to receive the thread at the proper time; also to project and retract 20 the needles to throw-off the stitches when the fabric is to be cleared from the needles.

The mechanism for controlling the knitting cam 90 (see Figures 2, 14, 15 and 16) consists of a shaft 116 journaled in the 25 blocks 71', the shaft being normally moved in a direction to move the cam 90 into knitting position. A pair of latches or detent pawls 117 and 118, mounted on supports 119, are adapted to engage with a rock arm 30 120 to hold the cam against the stress of the spring 116' in a half-way position, or fully in, as required. In their half-way position, i. e. when held by the pawl 118, the hooks 112 of the needles receive the thread as for 35 forming tuck stitches. An arm 121, fixed to shaft 116, is actuated by the trip or stop 114 to move the cams all the way in. The two latches 117 and 118 are provided respectively with extended portions 122 and 40 123 that may be engaged in succession by the trip 114 to permit the shaft 116 to actuate the link 87 and move the cams 90 and 91 into their outermost positions, i. e., the position for rib knitting.

45 A characteristic stocking made on my improved machine may consist of a ribbed leg, with a plain instep, sole, heel, and toe, such stockings being made in continuous succession as so-called string work, the successive 50 stockings being separated by a number of courses of long loose stitches providing ravel courses at the point of separation. Fig. 1^a of my co-pending application No. 146,917 filed Feb. 6, 1917, shows such a stocking in 55 which there is a ribbed leg and a plain foot. The stocking may have, near its top a round welt or a flat welt in half cardigan stitch, the welts in the stocking here discussed being merely for purposes of ornament, and 60 indicating some of the possibilities inherent in the machine.

The process of making such a stocking is as follows: beginning at the toe, first, a toe pocket is knitted on the cylinder needles only, then the machine changes to a rotary

movement for the foot which is knit in plain fabric on the cylinder needles. Then the heel pocket is knitted in the same manner as the toe pocket and a number of courses of plain fabric are knitted round and round 70 following the heel.

To change from plain fabric in the foot to rib fabric for the leg, the dial needles are now advanced to open their latches, disk 108 being raised to engage arm 107 and move out cam 90'. The needles engage brush 109 as they advance, and the machine makes one or more revolutions so that all latches may be opened, the knitting cam 90 being at this time in retracted position. Disk 114 now engages arms 113 and 115 to return cam 90' to idle position and the dial needles are advanced at the knitting side of the machine to tuck position, disk 114 being raised to engage member 122 to release hook 117, when the cam 90 and its plate will be moved by spring 116' toward knitting position, hook 118 engaging arm 120 on the shaft 116 to prevent the needles going all the way to knitting position. The dial needles now take the yarn and after all are supplied disk 108 engages arm 121 to return the needles to inactive or welting position, the hook 117 again engaging arm 120 on shaft 116 to hold the cam in place. The machine now makes one or more revolutions and then disk 114 is raised and successively releases hooks 117 and 118 to permit spring 116' to swing the post 116 to extreme position carrying cam 90 to knitting position. The purpose of taking the yarn by the dial needles a little prior to beginning rib knitting is to close the eyelet holes which otherwise result at this point.

Rib knitting now continues throughout the leg up to the point where a tuck welt is to be made. At this point the disk 108 moves arm 121 so as to be caught by hook 118, the cam 90 being moved half way in and the dial needles now tucking while the cylinder needles knit as before. When each dial needle has taken one or more extra loops of yarn, the whole is knit off to form a course of dial tuck stitches by raising disk 114 to release hook 118 so that cam 90 can knit, and this sequence of operation is repeated so long as tucking is to continue. A tuck welt or section of desired width having been made, plain rib knitting is resumed, and thereafter a round welt is made by raising disks 108 and 114 to release both hooks 117 and 118 in close succession, thus throwing the dial needles out of action but without casting off their loops. One or more courses are now knitted on the cylinder needles and the dial needles are returned to knitting position.

Rib knitting is resumed up to the top of the leg. The change from rib to plain knitting on the cylinder needles is now made as follows:

Disk 108 is raised to strike arm 121 and move the cam 90 and the dial needles to tucking position. After an additional revolution or two disk 114 strikes arm 121 and moves the cam 90 and the dial needles all the way in to inactive position, the shaft 116 being held by hook 117. The dial needles have now ceased knitting, but hold their loops. To cast off these loops, cam 90' 10 is now operated, disk 108 actuating arm 107 to move casting off cam 90' all the way out to clear the latches of the dial needles, and disk 114 then returning the cam by two steps by striking arms 113 and 115 in succession. Plain knitting is now resumed, the movement of the machine again being changed from rotary to oscillatory to begin the toe of the next stocking.

Many variations may be made in the product of the machine by the use of my improvements, as such use is not limited to the making of stockings, being equally applicable to machines for making underwear, sweater sleeves and other articles. Changes 25 in the design of the article may also be made in numerous ways, by varying the pattern devices to produce such effects as may be desired.

It is to be noted that my machine is adapted to start knitting on the bare needles. In the ribbers commonly in use it is necessary to thrust the stitches of a piece of fabric on both sets of needles to form a foundation on which knitting may begin, one reason 30 therefor being that the knitting waves of dial and cylinder needles are not simultaneous.

The presence in my machine of sinkers or webholders such as are used in plain knitting machines enables me to start knitting on the bare needles without resorting to a transfer or stabbing-on of fabric.

A rod 124 has vertical movement in the bearing 125 on the plate 126 secured to the 45 frame 25. The upper end of this rod carries rotary disks 108 and 114 forming abutments adapted to be lifted into the path of movement of the several arms 107, 113, 121, 122 and 123 of the above-described mechanism, in proper timed relation, through the rod 127 working in the sleeve 128 and having a lateral portion 129 that engages the underside of the disk 114. The lower end of said rod 127 rests on lever 130 pivotally 50 mounted on the frame 25 and which lever has a depending member 131 that co-operates with projections 132 carried on the pattern wheel 133 which is journaled loosely on the hub 134 of the ratchet 45. The ratchet wheel 60 is intermittently operated after the manner heretofore described; and said ratchet wheel operating means simultaneously moves the pattern wheel. The pattern wheel is constructed virtually as a mutilated ratchet wheel on which the pattern screws 132 and

teeth 135 are located, leaving blank spaces. While pawl 249 reciprocates idly on such a space the wheel stands still and to start the wheel again after the desired interval, a plurality of lugs 136 are formed on the 70 pattern wheel and engage with lugs 137 carried by the chain 48.

In the ordinary process of knitting hosiery, the toe and heel portions of the foot are knitted with three threads, while the foot 75 portion is knitted with only two threads; and for bringing the third thread into and out of operation, knitting machines have the yarn carrier adapted to be automatically actuated through a cam slot 138, formed in the cam wheel 65 on the shaft 44 (see Figures 1 and 6). Said cam slot 138 is usually provided with two salients, one for controlling the machine to knit the toe portion with three threads, and move the yarn carrier out 80 of position, and the other salient is to move the yarn carrier into position again for knitting the heel portion of the stocking with three threads, and then move the yarn carrier out of position when the body of the 85 stocking is knitted with two threads. But in ordinary plain knitting machines there are enough cylinder needles to form the foot portion of the desired texture, but in the present machine the number of cylinder 90 needles is less than that on ordinary plain knitting machines by reason of the dial needles, which must bear a definite ratio thereto. By reason of this lesser number of needles on the cylinder, it is proposed to 100 knit the entire foot of the stocking, the heel, toe and that portion between the heel and toe, of uniform texture or tension throughout to compare with the rib portion of the stocking.

To carry out the foregoing, it is therefore necessary to move the yarn carrier but once into position, or when the foot of the stocking is to be formed. To this end the cam wheel 65 has but one salient 139, which acts 105 on the shaft 140 of the yarn carrier (not shown) to move the latter into position for knitting the entire foot portion of the stocking, and then to move the same out of position when the remainder of the stocking is 110 being knitted.

The present invention further contemplates the provision of an automatic release for the drive in the event of breaking of either a cylinder needle or a dial needle, 115 which would cause an accumulation of thread or yarn and result disastrously to the machine. The apparatus for producing this result (see Figures 1, 2, 3, 7, 20 and 21) consists of an arm 141 pivotally mounted at 120 142 to the revolving head and normally held in inactive position by the lug 143 engaging the notch 144. A stud 145 carried at the free end of said arm 141 is adapted to engage with the lever 149, and move the latter 125 130

to disengage the end 150 latched in the notch 151 of the rod 152 that is normally tensioned to move downwardly by the spring 153. Said rod 152 is adapted to engage with 5 and release the latch plate 154 which is pivotally mounted on plate 156 from the stop 155 and allow the plate 156 to be moved longitudinally by the spring 157, carrying with it the belt guide 158 fixed thereto to 10 shift the driving belt from the driving pulley on to the idler pulley. It will therefore be seen that any accumulation of thread, due to a broken needle, or from other cause, will act against the immediately adjacent sinker 15 159 and thereby radially displace said sinker as indicated in Figure 8 to engage the cam portion 160 of the lever 141 and move said lever to the position shown in full lines in Figure 6 when the aforesaid operation will 20 occur.

The take-up apparatus for the machine consists of the usual pair of corrugated rollers 161 journalled in the frame 162 that is 25 swingingly mounted on the shaft 163 which is in turn journalled on the bracket 164 secured to the frame 25 of the machine. Said corrugated rollers 161 have inter- 30 geared pinions 165, and a pinion 166 on the roller shaft 167 is connected to be driven from the smaller pinion 168 on the shaft 169 that carries the pulley 170. A belt 171 connects the pulley 170 with the driven pulley 172 on the shaft 26. This apparatus is 35 a well known type and no claim thereto is made in the present application.

An auxiliary feeding or take up apparatus Figures 1, 6, 8 and 9 is employed in connection with the take-up just described and is adapted to be operated for continuously 40 feeding the stocking when the same is knitting the toe or heel portions, and at such times the take-up rolls 161 are in effect inactive. The annular take-up consists of a belt 173 carrying cross pieces 174 and traveling on two notched pulleys 175 and 176 that are journalled in the frame 177. Said frame is in turn mounted on a shaft 178 carried by a bracket 179 that is secured to a vertical post or shaft 225, herein shown as being 45 that shaft of the Mayo machine which is moved up and down to vary the stitch length, and is oscillated to operate the yarn changing devices.

The belt 173 is connected to be continuously driven by means of a gear wheel 180 50 fixed to the shaft 178 and meshing with a similar gear wheel 181 on the shaft 182 in the frame 179. A ratchet 183 fixed on the shaft 182 is intermittently rotated through 55 the medium of a pawl 184 on the arm 185 fulcrumed on the shaft 182, and said arm 185 has an extended portion 186 that carries a rod 187 having its free end movable in an apertured portion 188 formed with the 60 bracket 179. The rod 187 is reciprocated in

one direction by the arm 189 mounted on the pivot 253 of the hub 53 and the segment gear 39 and the reverse movements of said rod 187 are effected by the spring 190 mounted thereon and seating against a stop 70 191 and an anchor piece 192. It will therefore be seen that the operations of the arm 189 will cause the pawl 184 to be moved in a counter clockwise direction and will at the same time compress the spring 190, so that 75 said spring will in turn cause the pawl 184 to be advanced in a clockwise direction and turn the ratchet wheel 183 which through the gearing 180 and 181 will cause the belt 173 to be continuously driven. 80

It is obvious that those skilled in the art may vary the details of construction and form and arrangement of parts without departing from the spirit of my invention, and therefore I do not wish to be limited 85 in any such features except as may be required by the claims.

Having thus fully described my said invention, what I claim as new and desire to 90 secure by Letters Patent, is:

1. In a pattern mechanism for dial and cylinder knitting machines a pattern wheel having ratchet teeth at spaced intervals about its periphery, and a plurality of concentric series of projections on one side of the wheel, one or more of said series operating dial cam controlling means, substantially as set forth. 95

2. In a pattern mechanism a pattern wheel having ratchet teeth at spaced intervals, about its periphery, and a plurality of concentric series of projections on one side of the wheel, one of said series forming driving means supplementary to the ratchet teeth. 100

3. In a pattern mechanism, a pattern device having ratchet teeth at spaced intervals about its periphery, a driving pawl co-acting therewith, a pattern chain having means engaging said device to act as a supplementary drive, a lever pivoted adjacent said device and means projecting laterally from said device for engagement with said lever. 105

4. In a pattern mechanism, a pattern form having driving devices at spaced intervals on its periphery, supplementary driving devices projecting laterally therefrom and means also projecting laterally therefrom for engagement with elements to be controlled by the pattern. 115

5. In a pattern mechanism, a pattern wheel having teeth at spaced intervals on its periphery, means for co-acting therewith to drive the pattern wheel, a plurality of series of projections at one side of the pattern wheel, and a pattern chain co-acting with one set of projections to drive the wheel. 125

6. In a dial and cylinder knitting machine having dial and cylinder needles and oper- 130

- ating means therefor including movable dial cams, a pattern mechanism for controlling the operation of the needles to produce ribbed plain circular and reciprocating work in predetermined order said pattern mechanism comprising a vertically movable dial-cam-adjusting abutment, a main camshaft, a pattern wheel freely rotatable thereabout, and connections from the pattern wheel to 10 said abutment, substantially as set forth.
7. In a dial and cylinder knitting machine having dial and cylinder needles and operating means therefor including movable dial cams, a pattern mechanism for controlling 15 the operation of the needles to produce ribbed plain circular and reciprocating work in predetermined order said mechanism comprising a vertically movable dial-cam-adjusting abutment, a main camshaft, a pattern wheel freely rotatable thereabout, means for actuating the camshaft and the pattern wheel independently of each other, and connections from the pattern wheel to said abutment, substantially as set forth.
- 20 8. A knitting machine as in claim 6, with main and supplementary driving means for the pattern wheel, substantially as set forth.
9. In a knitting machine having a dial cap and movable cams thereon, means for 25 adjusting said cams comprising a movable abutment, a main cam shaft, a pattern wheel rotatable on the cam shaft, a vertical rod carrying said abutment, a lever in contact with the rod and projections on the pattern 30 wheel adapted to engage the lever and thus move the rod and the abutment, substantially as set forth.
- 35 10. In a knitting machine having a dial cap and movable cams thereon, means for 40 adjusting said cams comprising movable abutments, a pattern mechanism comprising a cam shaft, a hub loose thereon, a sprocket on the hub, a chain on the sprocket, a pattern wheel loose on the hub, means for 45 driving the cam shaft, the hub and the pattern wheel independently of each other, said means for driving the pattern wheel including intermittently operating connections 50 between the chain and the pattern wheel, and connections between the pattern wheel and said movable abutments, substantially as set forth.
- 55 11. In a knitting machine having a dial cap and movable cams thereon, and means 60 on the dial for controlling the positions of the cams, a pattern mechanism comprising movable disks for engagement with the controlling means for said cams, a main cam shaft, a hub loosely mounted thereon, a ratchet and a sprocket fixed to the hub, a pattern chain on the sprocket having lugs 65 at one side of certain links, a pattern wheel 70 loose on the hub, means for driving the pattern wheel including ratchet teeth thereon with blank spaces between certain teeth, a series of lugs on the pattern wheel adapted to be engaged by the lugs at the side of the pattern chain, another series of lugs at the side of the pattern wheel, a lever for engagement by the last named lugs, a slideable rod resting on the lever having a lateral extension at its upper end, said extension operating said disks, substantially as set forth.
- 75 12. In a knitting machine having a dial cap and movable cams thereon, and means on the dial for controlling the positions of the cams, a pattern mechanism comprising movable disks for engagement with the controlling means for said cams, a main cam shaft, a hub loosely mounted thereon, a ratchet and a sprocket fixed to the hub, a pattern chain on the sprocket having lugs 80 at one side of certain links, a pattern wheel loose on the hub, means for driving the pattern wheel including ratchet teeth thereon with blank spaces between certain teeth, a series of lugs on the pattern wheel adapted to be engaged by the lugs at the side of the pattern chain, another series of lugs at the 85 side of the pattern wheel, a lever for engagement by the last named lugs, a slideable rod resting on the lever, and connections from said rod to said disks, substantially as set forth.
- 90 13. A pattern mechanism for knitting machines comprising a main cam shaft, a ratchet thereon, a hub loose on the shaft, a ratchet and a sprocket fast to the hub, a chain on the sprocket, a pattern wheel loose 95 on the hub, a rocking member on the machine, pawls actuated at each oscillation thereof to drive the cam shaft and the hub, a pawl actuated twice for each oscillation of said member to drive the pattern wheel and controlling devices for the pawls driving the cam shaft and the pattern wheel, substantially as set forth.
- 100 14. In a pattern mechanism for knitting machines comprising a main cam shaft, a hub loose on the shaft, a timing device on the hub, a pattern form loose on the hub, a rocking member on the machine, independent means actuated thereby to drive the shaft and the timing device, independently driven means to drive the pattern form, means for disabling said driving means for the shaft and the pattern form and connections from the timing device for restoring said driving means to action, substantially as set forth.
- 110 In witness whereof, I have hereunto set my hand at Washington, District of Columbia this twentieth day of November, A. D. nineteen hundred and nineteen.
- 115 NAPOLEON J. PERRY.
